UNITED STATES PATENT OFFICE.

LUTHER M. FEATHERS, OF JOHNSON CITY, TENNESSEE, ASSIGNOR OF ONE-HALF TO
CARMON S. BOWERS, OF JOHNSON CITY, TENNESSEE.

PUNCH FOR ATTACHING LABELS, ETC.

Application filed September 27, 1927. Serial No. 222,324.

My invention relates to means for branding, marking or tagging articles of merchandise, but more particularly it has reference to a hand-actuated punch, of novel construction, for applying labels bearing suitable inscriptions directly to the pages of account and other books, including individual ledger sheets of banks or similar institutions.

When used in banks and banking institutions, one principle of the present invention is to insure accuracy and facilitate book-keeping. In the latter uses it has for a further object to enable a depositor or customer to place his or her customary signature upon an individual tag or tab of paper or other suitable material, and by means of the punch aforesaid to quickly apply such original specimen signature directly to the surface of an individual ledger sheet, other records or account books, so as to be plainly visible at all times.

With the foregoing and other objects in view, my improved punch will be herein-after particularly described, and then pointed out in the appended claims.

In the accompanying drawings which form part of this application for Letters Patent, and whereon like numerals indicate corresponding parts in the several views:

30 Figure 1 is a side elevation of my complete punch fully equipped and ready for use.

Figure 2 is a plan view of the punch base, and a horizontal section taken on the line 35 2-2 of Figure 1, with punch in its normal raised position.

Figure 3 is a view corresponding with Figure 1 except that the punch has been depressed as in the first label or tag attaching 40 operation.

Figure 4 is a view, partly in plan and partly in section, on the line 4-4 of Figure 3.

45 Figure 5 is also a detail horizontal sectional view, taken on the line 5-5 of Figure 3.

Figures 6, 7, 8 and 9 are each fragmentary views in front elevation showing successive steps in the process of affixing a tab or tag to the head of an individual ledger sheet, for example.

Figure 10 is a plan view of a presser foot.

Figure 11 is a vertical sectional view 55 through the gauge locking means taken on the line 11-11 of Figure 3, and

Figures 12 and 13 respectively show in plan two forms of tabs or labels employed.

Reference being had to the drawings and numerals thereon, 1 indicates the hollow base of punch having a rearward extension 2 in the center of which latter, upon a horizontal screw pintle, is journaled the inwardly-extending circular knuckle 3 upon one end of an upstanding, outwardly-extending arm 4, shouldered angularly, as at 5 and 6, as shown by Figures 1 and 3. The said knuckle 3 is engaged on one side of its pivotal center by the free ends of a spring 7, which serves to retain the operating arm 4 normally raised, as shown by Figure 1.

At its outermost end the operating arm 4 is provided with an integral enlargement or boss 8, having laterally projecting sides 9, 9, each perforated vertically as at 10, for purposes that will later appear. The said boss 8 is also perforated centrally, as at 11, to receive a reciprocating hollow plunger 12, surmounted by a bulbous enlargement or head 13, also hollow, as best shown by Figure 7 of the drawings.

At opposite ends the tubular plunger 12 is fitted interiorly with upper and lower washers 14, in which is centrally mounted a presser-foot rod 15, capable of independent reciprocation, and having rigidly secured thereto at a point below its longitudinal center a collar 16. Surrounding the said rod 15, and interposed between its collar 16 and the uppermost of the relatively fixed washers 14, is a coil spring 17 normally under compression, and serving, when required, to project the rod 15. Upon the upper end of this rod 15 is formed a barb 18 engaged by a spring-pressed latch 19 to normally retain the rod 15 in retracted position, as shown by Figure 7, and projecting transversely through the plunger-head 13 is a releasing push-pin, by means of which pin the latch 19 may be pushed from beneath barb 18 as the latch-spring 21 is compressed.

To the opposite or advance end of the rod 15, by means of an upwardly projecting boss 22, also serving as a limiting stop, is securely attached a presser-foot or stripper plate 23, shown in plan by Figure 10 of the drawings. 105 This presser-foot is formed of relatively stiff sheet metal, and is preferably rectangular in shape, is cut back as at 24 in its front edge, and configured upon its remaining edges by depressions 25 to permit passage of certain 110

punching blades, as will appear. It may also be perforated upon opposite sides of its boss 22, as at 26, 26; thus affording passage-way for the bit of a screw driver (not shown) when required.

Rigidly secured to the lower extremity of the tubular plunger 12 is a plunger head 27, made either of cast or sheet metal and relatively thick, having rigidly affixed thereto a pair of oppositely disposed upstanding guide pins 28, 28, loosely fitted within the apertures 10, 10, in the side members 9, 9, forming parts of the boss 8 aforesaid, for the purpose of guiding said plunger-head and dependent parts in their independent downward movement when occasion requires.

Secured in operative position, as by machine screws 29, at the sides and back of the plunger head 27, are depending knives 30 projecting through and normally beyond the presser-foot 23 aforesaid, while in the front slot 24 is positioned another knife 31, all of said knives having a roughened inner face, or a shallow V-slot as shown at 30' for purposes which will be set forth in a statement of operation hereinafter, the latter knife 31 being adjustable and mounted substantially as follows:

Projecting forward centrally from plunger head 27 is a gauge-bar 32 best shown by Figures 1, 3, 4, and in cross section by Figure 11. This bar 32 is provided with a stop pin or limit stud 33 near its outer extremity, its upper surface being broken by outer and inner transversely arranged pockets or half round depressions 34 and 35 respectively. Mounted upon the bar 32, and surrounding the same, as best shown by Figure 11, is an angular slidable block 36, to the inner face of which is securely attached the depending knife blade 31 aforesaid. Passing transversely through block 36 is a slideable locking pin 37 of cylindrical form in the main, but having a sector as at 38 cut from same intermediate its ends 39 and 40, which portions of the pin are full round. Secured beneath block 36 also, as by the machine screw 41, is a small spring 42, the free or outermost end of which bears upon the shouldered head of pin 37 to yieldingly retain it in its normally locked relation as shown by Figure 11 of the drawings. When it is desired to adjust the position of knife 31, the pin 37 is withdrawn against the pressure of spring 42 until its cylindrical portion 40 clears the half round groove 35 in face of the adjusting bar 32.

At this time the inner end of cylindrical portion 39 of said pin will bear against one side of the bar 32, and in this relation of parts the knife-carrying block 36 may be advanced upon bar 32 until pin 37 reaches the outer half round depression 34, into which the round end 40 of pin 37 will then be projected by action of the spring 42 to again lock knife 31 in its outermost adjusted position, and it

will be obvious that intermediate adjustments may be made in like manner provided only that intermediate depressions such as 34 are formed in the surface of bar 32 intermediate of the two shown.

70

The hollow base 1 is formed with a top 43 and a slightly depressed working surface 44, the latter of an outline to fit either small or large tags 45 or 46 of relatively stiff paper, or preferably celluloid blanks unglazed on one side to form a writing surface, as shown by Figures 12, 13 respectively, and for uses which will appear in a description of operation to follow. The tags or tabs 45 and 46, or any such as may be used with my invention, are provided with integral end and side projections or tongues 47, 48, respectively, as fastening means.

The top 43 is broken at points 49, 49, 50, 50, and at 51 by angular openings adjacent the depressed working surface 44 aforesaid for purposes which will also later appear.

The structural features of my present invention being substantially as shown and described, its primary object is that of quickly, accurately and securely, but at the same time removably attaching tags or tabs such as indicated by Figures 12 and 13 for example, suitably inscribed or autographed, to records, record books, account books, with temporary or permanent pages, or other articles requiring marking, branding, or a display memorandum; and, for purposes of the description of operation to follow such an article by way of exemplification is illustrated in Figures 8 and 9 of the drawings, as a loose-leaf individual bank ledger sheet 51.

95

The invention in one approved form of embodiment, being substantially as shown and hereinbefore described, its use and operation will now be briefly set forth as follows:

105

It being desired to utilize a tag or tab such as 45, preferably of celluloid having at least one unglazed surface and cut to the dimensions and form shown at 45, Figure 2; and, it being further desired to employ such tag for displaying a visible specimen signature of a depositor and to apply same to the individual ledger of a banking institution, the tag 45 is first placed in the slightly depressed position indicated by Figure 2. The punch arm 4 is then rocked upon its pivotal support from the normal position of Figure 1 to the position indicated by Figure 3, where it is arrested by engagement of the shoulder 5 with the top plate 43.

115

Downward pressure applied to the head 13 now causes the hollow plunger 12, with depending parts, to descend, thereby folding the tongues 47, 47 of the blank 45 through openings 49, 49 in the top plate 43 as shown by Figure 6. By this downward movement also latch 19 is caused to engage beneath the barb 18 as shown, whereupon head 13 being

120

125

130

released, is lifted to the position shown by Figure 7 through reaction of the main spring 53, the tag 45 being picked up, and retained between the side blades 30, 30, 30 and 31 as shown, the roughened inner faces or V-grooves 30' facilitating retention of the tags 45 when in the position indicated by Figure 7.

At this time the individual ledger sheet 52 is laid upon top plate 43 as indicated by Figures 8 and 9. Pressure again applied in a downward direction to the bulbous head 13 and depending parts, causes the plunger head 27 to again descend as before, and as now shown by Figure 8, the blades 30 and 31 this time pierce the sheet 52 adjacent the said tongues 47, 47 and 48, 48. By the latter operation also these tongues 47 and 48, are not only folded into the apertures thus formed in the ledger sheet, but at the same time pressure upon the push pin 20 releases the central spring pressed plunger 15 causing it to forcibly descend under influence of its spring 17, until the presser foot 23 effectively and smoothly spreads and forces the said tongues into the locked relation to the sheet 52 shown by Figure 9.

The foregoing being a description of my invention, its use and operation, in one approved form of construction, it should be understood that various changes in the size, form and structural arrangement of parts shown may readily be made and substituted for those shown without in the least departing from the spirit of my invention as set forth by the appended claims.

Having thus set forth the present invention, what I now claim and desire to secure by Letters Patent is:

1. In a punch of the character described the combination with a base, having a depressed working surface broken by knife-receiving slots, of a plunger surmounting said base, and a series of knives carried by said plunger arranged and adapted to enter said slots when the plunger is depressed.

2. In a punch of the character described the combination with a hollow base having a depressed working surface broken by disconnected knife-receiving slots, of a plunger surmounting said base, and a series of knives depending from said plunger arranged and adapted to enter said slots when the plunger is depressed.

3. In a punch of the character described the combination with a base having a tag-holding depression in its working surface, a series of knife receiving slots surrounding said depression, a plunger surmounting said base, and a series of knives carried by said plunger arranged and adapted to enter said slots when the plunger is depressed.

4. In a punch of the character described the combination with a hollow base having a working surface broken by knife-receiving slots, of a plunger surmounting said base,

and a series of knives depending from said plunger having roughened inner surfaces near their advance ends arranged and adapted to enter said slots when the plunger is depressed and to pick up between such roughened surfaces a tag to be operated upon.

5. In a punch of the character described the combination with a base having a working surface broken by knife-receiving apertures, an operating arm pivotally secured to said base and overhanging at its outer end the said working surface, a plunger reciprocally supported in the outer end of said arm, and a series of knives carried by said plunger arranged and adapted to enter the apertures aforesaid when the plunger is depressed.

6. In a punch of the character described the combination with a base having a working surface broken by knife-receiving apertures at predetermined points, an operating arm pivotally secured to said base and extending over the said working surface, a spring retracted plunger reciprocally supported in the free end of said arm, and a series of knives depending from said plunger arranged and adapted to enter the apertures aforesaid when the plunger is depressed.

7. In a punch of the character described the combination with a hollow base having a working surface broken by knife-receiving apertures at predetermined points, an operating arm pivotally secured to said base and extending over the said working surface, a spring for retaining said arm normally in raised position, a plunger reciprocally supported in the free end of said arm, and a series of knives depending from said plunger arranged and adapted to enter the apertures aforesaid each time the plunger is depressed.

8. In a punch of the character described the combination with a hollow base having a working surface broken by knife-receiving apertures at predetermined points, an operating arm pivotally secured to said base and extending over the said working surface, a spring for retaining said arm normally in raised position, a plunger reciprocally supported in the free end of said arm, a spring for returning the plunger to normal position after each operation, and a series of knives depending from said plunger arranged and adapted to enter the apertures aforesaid each time the plunger is depressed.

9. In a punch of the character described the combination with a hollow base having a working surface broken by knife-receiving apertures at predetermined points, an operating arm pivotally secured to said base and extending over the said working surface, a spring for retaining said arm normally in raised position, a plunger reciprocally supported in the free end of said arm, a spring surrounding said plunger for returning it to normal position after each operation, and a

- series of knives having shearing ends depending from said plunger arranged and adapted to enter the apertures aforesaid each time the plunger is depressed.
- 5 10. In a punch of the character described the combination with a base having a working surface broken by knife-receiving apertures at predetermined points, an operating arm secured to said base and extending over the said working surface, a plunger reciprocally supported in the outer end of said arm, a plunger-head attached to and moving with the plunger, and a series of knives depending from said plunger-head arranged and adapted to enter the apertures aforesaid each time the plunger is depressed.
- 10 11. In a punch of the character described the combination with a base having a working surface broken by knife-receiving apertures at predetermined points, an operating arm secured to said base and extending over the said working surface, a boss upon the outer end of said arm, a plunger reciprocally supported in said boss, a plunger-head connected to the end of said plunger, guide-pins extending loosely from the plunger-head through the said boss, and a series of knives depending from said plunger-head arranged and adapted to enter the apertures aforesaid each time the plunger is depressed.
- 15 12. In a punch of the character described the combination with a base having a working surface broken by knife-receiving apertures at predetermined points, an operating arm secured to said base and extending over the said working surface, a plunger reciprocally supported in the outer end of said arm, a plunger-head beneath the plunger, and a series of knives depending from said head each having an angular lower end and roughened inner surface arranged and adapted to enter the apertures aforesaid each time the plunger and plunger-head are depressed.
- 20 13. In a punch of the character described the combination with a base having a working surface broken by knife-receiving apertures at predetermined points, an operating arm secured to said base and extending over the said working surface, a hollow plunger reciprocally supported in the outer end of said arm, a plunger-head beneath the plunger, and a series of knives depending from said head arranged and adapted to enter the apertures aforesaid each time the plunger and plunger-head are depressed.
- 25 14. In a punch of the character described the combination with a base having a working surface broken by knife-receiving apertures at predetermined points, an operating arm secured to said base and extending over the said working surface, a hollow plunger reciprocally supported in the outer end of said arm, a plunger-head beneath the plunger, a series of knives depending from said head arranged and adapted to enter the apertures aforesaid each time the plunger and plunger-head are depressed, a spring pressed rod extending through the hollow plunger and plunger-head, and a presser-foot upon the advance end of said rod as and for the purposes specified.
- 30 15. In a punch of the character described the combination with a base having a working surface broken by knife-receiving apertures at predetermined points, an operating arm secured to said base and extending over the said working surface, a hollow plunger reciprocally supported in the outer end of said arm, a plunger-head beneath the plunger, a series of knives depending from said head arranged and adapted to enter the apertures aforesaid each time the plunger and plunger-head are depressed, a spring-pressed rod extending concentrically through the hollow plunger and plunger-head, a presser-foot upon the advance end of said rod, means for retaining said rod and presser-foot in retracted position, and means for permitting the latter to be projected under action of its surrounding spring.
- 35 16. In a punch of the character described the combination with a hollow base having a depressed working surface broken by disconnected knife-receiving slots lying in the perimeter of a polygon, of a plunger surrounding said base, and a series of knives carried by said plunger arranged and adapted to enter said slots when the plunger is depressed.
- 40 In testimony whereof I affix my signature.
LUTHER M. FEATHERS.
